UNITED STATES PATENT OFFICE.

HENDRIK J. VAN DER BIJL, OF NEW YORK, N. Y., ASSIGNOR TO WESTERN ELECTRIC COMPANY, INCORPORATED, OF NEW YORK, N. Y., A CORPORATION OF NEW YORK.

THERMIONIC DEVICE.

Application filed September 4, 1919. Serial No. 321,653.

To all whom it may concern:

Be it known that I, HENDRIK J. VAN DER BIJL, a subject of the King of Great Britain, residing at New York, in the county of New York and State of New York, have invented certain new and useful Improvements in Thermionic Devices, of which the following is a full, clear, concise, and exact description.

This invention relates to thermionic devices and a method for making the same, and concerns particularly the manufacture of audions.

An object of the invention is to avoid the necessity of sealing-in a flare to a main bulb structure, as has heretofore been the custom.

Another object is to provide an improved simple mounting whereby the electrodes may be rigidly assembled prior to insertion in the bulb or tube, and may then be readily and, in a simple manner, placed within the tube.

The invention in general comprises mounting and assembling the electrode structure, prior to its assembly within the tube, on a framework comprising a plurality of rigid wires, which have been previously definitely spaced. The rigid space relation of these wires, from which the electrodes are supported, is maintained by connecting them through the intermediary of an insulating and supporting connection such as a bead of glass.

After the electrode unit has been thus assembled, the invention further comprises merely that this assembly be inserted into a glass tube, and, while held in the proper position within the tube, the open end of the tube itself is heated and is flattened out over the extension of the lead-in wires, thus sealing the unit within the bulb or tube without the usual re-entrant stem.

In the previous practice it has been found necessary to provide a flare on which a suitable stem or squash was formed, through which the lead-in wires were passed. The quantity production of these flares and squashes generally required expensive machinery. After the electrode unit was mounted on this stem or flare portion further expensive machinery has hereto been required to successfully seal-in the flare portion or stem unit to the main bulb structure.

As described above it will be noted that the equivalent or substitute for the usual stem portion is now formed from the lower

end of the tube itself, and that the means for mounting the electrodes in a definite spaced manner is provided in the glass bead above mentioned which preferably fits snugly within the bulb but is not integral therewith. In this manner several expensive operations in the previous manufacture of tubes are eliminated.

The invention is illustrated in the drawing in which Fig. 1 is a perspective view of a tube made in accordance with the invention; Fig. 2 is an elevation of part of the tube showing another arrangement wherein the insulating material is of a length substantially equal to the inner bore of the tube.

As illustrated in the drawing (Fig. 1) the invention comprises an evacuated vessel 1, which may be in the form of a bulb or in the form of a tube as shown. This vessel has its lower portion or stem 2 collapsed around a plurality of lead-in wires 3, 4, 5 and 6. These lead-in wires connect respectively to a plurality of rigid wires 7, 8, 9 and 10, which are formed as a frame member by being connected by a glass bead 11 or other insulating material which may be formed across these wires in any suitable or well-known manner. This insulation and supporting material may be of any desired length; for instance, in Fig. 1 it is of a length shorter than the bore of the tube but, as shown in Fig. 2, it may be of a length to fit snugly within the bore of the tube and thus serve as an additional means for maintaining the electrode unit rigid within the evacuated vessel. The rigid wire 10 extends above the glass bead 11 and is welded along its length to a cylindrical electrode 12, which in this case is an anode.

The rigid wire 9 extends above the glass bead 11 and is connected to the lower end of a spiral electrode 13, which in this case is a control electrode or grid. The rigid wire 7 extends above the glass bead 11 and, by means of a resilient spring member 14, is connected to the upper end of a filamentary electrode 15, which in this case is the cathode, the lower end of which cathode is connected to the upper end of rigid wire 8 above the glass bead. The spring member 14 provides means whereby the cathode may be maintained under a definite tension. The cathode is arranged substantially along the central axis of the tube and the other electrodes are arranged concentrically around it.

In the manufacture of this tube, the rigid

- wires 7, 8, 9 and 10 are held in a suitable frame member outside the tube, while the glass bead is being fused across them. After this is done the electrodes are mounted thereon, the glass connection serving to maintain the proper space relation between the electrodes, in lieu of the usual stem which is usually formed on the upper end of a flare portion.
10. When this assembly has been completed, the lead-in wires 3, 4, 5 and 6 are connected respectively to the lower ends of the rigid wires 7, 8, 9 and 10, and this assembly is then inserted within the tube. The lower end of the tube is then heated and a pair of pincers, or other suitable means, is used to flatten the lower end of the tube itself over the lead-in wires and thereby seal the assembly within the tube in a much simpler manner than has hereto been the case.
- What is claimed is:
1. An electron discharge device comprising a glass tube having one end collapsed to form an outwardly projecting flareless stem, a plurality of conductors sealed in said stem and a plurality of electrodes each supported by one of said conductors.
  2. An electron discharge device comprising a glass tube having a portion collapsed to form an outwardly projecting flareless stem, a plurality of conductors sealed in said stem, a plurality of electrodes each supported by one of said conductors and an insulating member secured to said electrodes whereby the space relation between the electrodes may be established before their insertion within the tube.
  3. In combination, a plurality of conductors, a plurality of electrodes each supported by one of said conductors and an enclosing vessel comprising a glass tube having one end collapsed about said conductors to form an outwardly projecting flareless stem.
  4. In combination, a plurality of conductors, a plurality of electrodes each supported by one of said conductors, an insulating member secured to said conductors whereby the space relation between said electrodes is established, and an enclosing vessel comprising a glass tube having one end collapsed about said conductors to form an outwardly projecting flareless stem.
  5. The combination of frame support members positioned parallel with respect to each other, electrode support members positioned parallel to and between said frame members, means for uniting said members to form an electrode unit, an electrode extended between aligned support members, an electrode supported by one of said frame members, and means for supporting said unit within an exhausted envelope.
  6. The combination of frame support members positioned parallel with respect to each other, electrode support members positioned parallel to and between said frame members, means for uniting said members to form an electrode unit, electrodes carried by said supports, and means for suspending said unit in an exhausted envelope.
  7. The combination of frame support members positioned parallel with respect to each other, electrode support members positioned parallel to and between said frame members, means for uniting said members to form an electrode unit, electrodes carried by said supports, and means for suspending said unit in an exhausted envelope by means of said electrode support members.
  8. The combination of a plurality of electrode supports, means for binding the same together to form an electrode supporting unit, electrodes carried by said supports, and means for supporting said unit within an exhausted receptacle, and leading-in wires on said support members and extending through said envelope.

In witness whereof, I hereunto subscribe my name this 28th day of August A. D., 1919.

HENDRIK J. VAN DER BIJL.
